WINDOW STRIP INSTALLATION AND
FASTENER FOR THE SAME

Wilmer H. Churchill, Saugus, Mass., assignor to
United-Carr Fastener Corporation, Cambridge,
Mass., a corporation of Massachusetts

Application March 25, 1937, Serial No. 133,011

3 Claims. (Cl. 24—73)

My invention relates to an improved fastener member for attaching a window strip or the like to a supporting structure.

Referring to the drawing, in which I have illustrated preferred embodiments of my invention:

Figure 1 is a top view of one form of my fastener member secured to a window guide strip;

Fig. 2 is a section of a window channel support, a window for the same and a window guide strip secured to the support by means of my first form of fastener member;

Fig. 3 is a top view of the fastener member shown in Figs. 1 and 2;

Fig. 4 is a section taken along the line 4—4 of Fig. 3;

Fig. 5 is a front view of the fastener shown in Fig. 3;

Fig. 6 is a bottom view of the fastener shown in Fig. 3;

Fig. 7 is a top view of a modified form of my fastener member;

Fig. 8 is a side view of the fastener shown in Fig. 7; and

Fig. 9 is a bottom view of the fastener shown in Fig. 7.

The object of my invention is to provide a simple yet efficient fastener member for attaching a flexible strip or the like to a supporting structure. Due to the fact that my improved fastener member is particularly useful for purposes of securing a window guide strip to a window channel supporting structure, I prefer to describe it in connection with such an installation although there are many other uses to which my fastener could be directed which would fall within the spirit of this invention.

Referring to Fig. 2, which illustrates the preferred use of my invention, I have shown a metal window channel frame 1, which may be of U-shaped construction in cross-section. The inside face 2 of the frame bounds one side of the channel through which a window pane 3 is moved during the raising and lowering of the same. A flexible strip 4 is positioned in predetermined

position relative to the outer end 2a of the frame 1 so as to seal in effective manner the passage between the frame face 2 and the window pane 3, as shown in Fig. 2. The strip which I have chosen for the purpose of illustrating my invention is of an elongated shape in cross-section and provided with a metal stiffening core 5 for preventing too great flexibility of the part. A nap means 6 is provided along one edge of the strip on the side facing the pane 3. A portion 7 of the body of the strip adjacent the opposite edge

of the strip from that along which the nap means 6 is disposed is adapted to be gripped by portions of a fastener member, in a manner to be herein-after described, so as to secure the fastener to the strip.

The strip 4 is attached to the frame 1 by means of my improved fastener members which are provided with a yieldable stud means 8 extending through an aperture 9 in the frame face 2 and engaging the material of the frame surrounding the aperture, as illustrated in Fig. 2. For reasons of manufacture the aperture 9 is disposed relatively near to the outer end 2a (Fig. 2) of the frame 1. Also, in order that the window guide strip installation may present a neat and attractive appearance, many automobile manufacturers insist that the strip be disposed, after attachment, substantially even with the outer end 2a of the frame 1 and not project beyond the same. My improved fastener is constructed in such a way that it may grip the strip firmly so as to secure it permanently to the frame and, at the same time, hold it in the required position relative to the outer end of the frame.

Referring in detail to my first form of fastener member, I have illustrated in Figs. 1-6 a fastener made of one piece of sheet metal presenting a base portion 10 and a yieldable stud portion 8 extending from the base. The base 10 is of substantially U-shaped construction providing an upper arm 11 and a lower arm 12 connected at their ends by an intermediate portion 13. The free ends of the arms 11 and 12 define an opening adapted to receive the thickness of the strip 4. The lower arm 12 is adapted to be clamped against an opposite side of the strip 4 from the arm 11 so as to secure the fastener to the strip and, in order to accomplish this purpose, the base 10 is preferably constructed to be yieldable at the intermediate portion 13 whereby the arm 12 is moved from full open position relative to the arm 11, when a suitable tool (not shown) is applied to it, in the direction of the arm 11 so that the arms embrace opposite sides of the strip. An upwardly extending gripping portion 14 is preferably provided at the free end of the arm 12 which is adapted to engage the body of the strip 4 (Fig. 2) so as to provide a more secure attachment.

In order that the strip may be positioned in proper relation to the end of the frame, as hereinabove described, when the parts of the installation are in final assembly, I have provided stop means in the form of lugs 15 (Figs. 4 and 5) integral, in my preferred form, with the clamping

arm 12 and positioned intermediate the free end of the arm and the intermediate portion so as to space the strip from the intermediate portion when the fastener is secured to the strip. The lugs 15 extend upwardly from opposed lateral edges of the arm 12 and have free end portions sheared, in my preferred form, from the material of the intermediate portion 13. The openings 16 adjacent lateral edges of the intermediate portion (Fig. 5), which are formed by taking material out of the intermediate portion to form the lugs, serve to reduce the width of the intermediate portion so as to increase flexibility of the same. The free end portions of the lugs are disposed between the arms 11 and 12 on the same side of the intermediate portion 13 as the opening defined by the free ends of the arms 11 and 12, as most clearly illustrated in Figs. 2 and 4. Thus it will be seen that by my invention I have provided a fastener having a clamping arm which is long enough to overcome appreciably the resistance against bending which is set up in the intermediate portion thereby enabling the arm to be moved more readily into clamping position. Also, my fastener presents positioning means in the form of the lugs 15, whereby the strip may be secured in proper position relative to the outer end of the frame.

As a means for securing the fastener member to a support I have provided the stud portion 8 which extends from the arm 11 and is adapted to be snapped through the aperture 9 of the frame structure 1. The stud portion 8, in my preferred form, comprises a yieldable loop of relatively narrow material integral with the arm 11 and disposed adjacent the inner end of a slot 17 cut into the arm 11 from the free end thereof. The loop comprises legs 18 and 19, each of which has a diverging portion and a converging portion providing shoulders for engagement with a cooperating apertured part (Fig. 4). The legs 18 and 19 are connected at their leading ends forming a nose 20 for guiding the stud means into engagement with a cooperating socket means. The end of the leg 19 opposed to that end connected to the leg 18 joins the material of the arm 11 adjacent the slot 17 and the end of the arm 18 opposed to that connected to the leg 19 is free so that the stud means may have proper resiliency. A flange 18^a is provided at the free end of the arm 18, in my preferred form, extending outwardly from the leg 18 and lying within the slot 17 in substantially the plane of the arm 11 (Figs. 4 and 5) whereby no portion of the arm 18 extends into the strip-receiving opening between the arms 11 and 12 so as to impede entrance of the strip between the arms.

Assembly of the component parts of my installation is a relatively simple matter and is accomplished by first moving the fastener toward the portion 1 of the guide strip 4 until the guide strip abuts the stop lugs 15. The lower arm 12 is then struck by a suitable tool to move it in the direction of the arm 11 so that the free end portion 14 of the arm engages the material of the strip and the strip is firmly gripped between the arms 11 and 12 (Figs. 1 and 2). As many fasteners as are needed to secure the guide strip in position may be assembled with the strip in the manner just described. The fasteners are assembled with the strip so that when the strip is brought into position for application to the frame support 1, a fastener will be approximately opposite an opening 9. Finally the guide strip is secured to the support by moving the yieldable loop-shaped

stud means 8 through the apertures 9 of the support whereupon the diverging portions of the legs 18 and 19 resiliently engage the material adjacent the apertures 9 (Fig. 2).

My modified fastener member illustrated in Figs. 7-9 comprises a U-shaped base having a pair of arms 21 and 22 adapted to grip opposite sides of the portion 1 of the body of the strip 4 and an intermediate portion 23 connecting the arms at their ends. A loop-shaped resilient stud member 24, which is similar in form to the stud 8 of my first form of fastener, extends upwardly from adjacent a free edge of the arm 21 for snap fastener engagement with an aperture 9 of the frame support 1. The free end of the stud 24 preferably has an outwardly extending flange portion 24^a lying substantially in an extension of the lateral plane of the arm 21. The arm 21 differs slightly from the arm 11 of my first form of fastener in that the length of the arm from a point adjacent the intermediate portion 23 to adjacent the junction of the stud 24 with the arm is greater than in my first form. As a result of this relatively long construction, the arm 21 provides a proper bearing service without the necessity of continuing portions of the arm 21 beyond the point at which the stud means joins the arm as provided in my first form for carrying out this object. In attaching the fasteners to the strip 4 the base is moved toward the strip until portions of the arms 21 and 22 are disposed on opposite sides of the strip. The lower arm 22 is then struck by a suitable tool so as to move it toward the arm 21 and into clamping engagement with the strip. This clamping action is enabled through reason of the flexibility of the intermediate portion 23 which may be apertured or reduced in width in some suitable manner so as to increase its yieldability.

In order that the strip 4 may be spaced from the intermediate portion 23 after it has been secured between the arms for the purposes mentioned in connection with the stop lugs 15 of my first form of fastener, I have constructed the lower clamping arm 22 so that it has a portion 25 extending from the intermediate portion 23 substantially in parallel relation to the arm 21 for a predetermined distance and an engaging portion 26 extending from the portion 25 downwardly and outwardly away from the arm 21 toward the opening in the base defined by the free ends of the arms. The portion 26, together with a portion of the arm 21, is adapted to engage opposite sides of the strip so as to secure the fastener to the same. Due to the fact that the distance between the portion 25 of the arm 22 and a portion of the arm 21 with which the portion 25 is parallel is less than the diameter of the portion 1 of the body of the strip, the strip is maintained in spaced relation to the intermediate portion 23 after it has been secured to the fastener. Thus by the particular manner in which I have formed my fastener I am enabled, as in the first form of my device, to secure the strip to the support in such a way that it is properly positioned relative to the outer end of the support and, also, I have provided, as described in connection with my first form of fastener, a strip-gripping base portion which is constructed in a way to have a lower clamping arm of sufficient length to enable it to be easily moved into proper clamping engagement with the strip.

As a result of my invention I have provided fastener members capable of satisfactory operation in connection with a specific installation of

the type illustrated and described and also other installations.

Although I have illustrated and described preferred forms of my invention, I do not wish to be limited thereby as the scope of my invention is best defined by the following claims.

I claim:

1. A fastener member comprising a base having a pair of yieldable arms and an intermediate portion connecting said arms at certain of their ends, the free ends of said arms opposite said connected ends defining an opening for receiving an article, one of said arms normally extending from said intermediate portion in substantially parallel relation to said other arm and then flaring outwardly from said other arm toward said opening, said outwardly flared portion adapted, in cooperation with a portion of said other arm, adjacent the free end of said other arm, to clamp upon opposite sides of said article, said parallel portions of said arms having a lesser distance between them than the thickness of said article whereby said article is spaced from said intermediate portion after it has been secured to said base.
2. A fastener member comprising a base and a

yieldable stud means extending from said base, said base having a pair of yieldable arms and an intermediate portion connecting said arms at certain of their ends, the free ends of said arms opposite said connected ends defining an opening for receiving an article, projections extending from one of said arms toward the other of said arms for limiting movement of said article in the direction of said intermediate portion whereby said article is spaced from said intermediate portion, at least the free end portions of said projections being formed from the material taken from said intermediate portion.

3. A fastener member comprising a base and a yieldable stud means extending from said base, said base having a pair of yieldable arms and an intermediate portion connecting said arms at certain of their ends, the free ends of said arms opposite said connected ends defining an opening for receiving an article, projections extending from one of said arms toward the other of said arms for limiting movement of said article in the direction of said intermediate portion whereby said article is spaced from said intermediate portion.

WILMER H. CHURCHILL.
